UNITED STATES PATENT OFFICE.

AUGUST MILLER, OF TAUNTON, MASSACHUSETTS, ASSIGNOR TO REED & BARTON CORPORATION, A CORPORATION OF MASSACHUSETTS.

DESIGN FOR A MOUNT FOR SILVERWARE.

No. 38,163.

Specification for Design.

Patented Aug. 14, 1906.

Application filed June 25, 1906. Serial No. 323,389. Term of patent 14 years.

To all whom it may concern:

Be it known that I, AUGUST MILLER, a citizen of the United States, residing at Taunton, in the State of Massachusetts, have invented a new, original, and ornamental Design for a Mount for Silverware, of which the following is a specification, reference being had to the accompanying drawing, forming a part thereof.

The figure is a plan view showing my new design for a mount for silverware.

I claim—

The ornamental design for a mount for silverware as shown.

AUGUST MILLER.

In presence of—

GEORGE E. CHAMBERS,
HERBERT O. WOOLLEY.
